UNITED STATES PATENT OFFICE.

ALBERT BOYD HUNN, OF BRISTOL, CONNECTICUT, ASSIGNOR TO THE NEW
DEPARTURE BELL COMPANY, OF SAME PLACE.

DESIGN FOR A GONG.

SPECIFICATION forming part of Design No. 32,920, dated July 10, 1900.

Application filed June 2, 1900. Serial No. 18,909. Term of patent 7 years.

To all whom it may concern:

Be it known that I, ALBERT BOYD HUNN, a citizen of the United States, residing at Bristol, in the county of Hartford and State of Connecticut, have invented and produced a new and original Design for Gongs, of which the following is a specification.

The design is shown in the accompanying drawings, in which—

10 Figure 1 shows a plan view, and Fig. 2 a sectional view taken on the line $x x'$.

As shown in the drawings, the leading and material feature of my design consists of a panel or field formed on the upper surface of 15 the gong of less area than the diameter of the top of the gong, with the surface within the panel or field roughened in order to impart

thereto a distinctive and characteristic appearance different from the finish imparted to the gong outside of the boundary of said panel or field.

Having thus described my invention, I claim as new and desire to protect by Letters Patent of the United States—

The design for a gong, substantially as 25 shown and described.

In testimony whereof I have signed my name to this specification in the presence of two subscribing witnesses.

ALBERT BOYD HUNN.

Witnesses:

F. B. SCUDDER,
ALICE E. BROWN.
